UNITED STATES PATENT OFFICE.

CHARLES H. NORTH, OF CLEVELAND, OHIO.

FOUNTAIN-PEN.

1,302,417.

Specification of Letters Patent. Patented Apr. 29, 1919.

Application filed March 29, 1915. Serial No. 17,624.

To all whom it may concern:

Be it known that I, CHARLES H. NORTH, a citizen of the United States of America, residing at Cleveland, in the county of Cuyahoga and State of Ohio, have invented certain new and useful Improvements in Fountain-Pens, of which the following is a specification.

My invention relates to improvements in fountain pens, and certain details which are more particularly applicable to a stylographic pen. The fountain pen embodying my invention comprises a stylographic point which preferably is provided with a jeweled tip, through which an adjustable wire is normally spring-pressed, while the tip section is provided with an indirect air vent which serves likewise as an inlet for the ink of the self-filling pen. The rubber ink bag is provided with a lateral depressing member 15 swinging freely from a U-shaped hanger engaging slots at the top of the pen barrel, which hanger is adapted to be engaged by an inserted coin entering through a slot in the barrel, for the purpose of depressing the ink bag. In order to avoid flooding, I have provided a slightly depressed channel upon the tip section, while a shoulder engages an elevated rim of the channel, and the tip engages a soft rubber stop, securely sealing the pen tip against the drying of ink when the cap is screwed into position.

These, with other features of my improvements, will be better explained by making reference to the accompanying drawings, wherein:—

Figure 1 is a view in longitudinal section, showing a stylographic pen equipped with my improvements.

Fig. 2 is a greatly enlarged end view showing the adjustable abutment for the feed wire.

Fig. 3 is an enlarged fragment partially in longitudinal section showing the self-filling mechanism.

Fig. 4 is an enlarged transverse section of the same on line 4—4 of Fig. 1.

Fig. 5 is an enlarged view of the tip-section, shown partially in longitudinal section, and

Fig. 6 is an enlarged section of the jeweled tip and mounting.

Throughout the several figures of the drawings I have employed the same character of reference to indicate similar parts.

Referring first to Fig. 1, it is seen that the

barrel *a* is slotted at *a'*, while partial diametrical slots *a''* are provided at the end thereof, which accommodate the extended terminals of a U-shaped hanger *b'* secured to the metal depressing strip *b*, which overlies the soft rubber ink bag *c*.

The mouth of the ink bag is slipped over the nipple *d'* of the intermediate section *d*, which section is threaded to screw into the barrel *a*, and which terminally carries the tip section *e*. Within a gold mounting sleeve *f'* there is provided a bored jeweled point *f* through which passes the feed wire *g*, so that its extremity extends slightly beyond the jewel, and serves to permit the flow of ink when said jewel point is pressed upon the paper. The rear of said wire is carried by a screw threaded block *g'* against which a spring *g''* re-acts normally, to press the wire 70 beyond the opening in the jewel. The sides of the block are cut away as shown in Fig. 2, so that an adjustment of the wire is thereby obtainable, and free access is afforded to the axial ink passage in the tip section.

The construction of the tip section *e* (best shown in Fig. 5) is peculiar to my improved pen, comprising as it does a valve-seating extremity, *e'*, adapted to engage the rear inclined walls *d''* of the intermediate section *d*, for which they form a seat. An annular channeled *e''* affords communication between the inner vent *e³* and the external vent *e⁴*, bored at opposite sides of the tip section. The latter vent communicates with the bottom of a tip channel *e⁵* which has a wall *e⁶* spaced apart from the rim of the intermediate section by a second channel, and the said wall is constructed approximately one thirty-second of an inch less in height than the rim *d''* of the intermediate section (see Fig. 1), whereby I am enabled to prevent flooding of the pen, and maintain the exterior of the tip section free from ink. The cap *h* is adapted to screw upon the barrel, and contains at its extremity a button *h'* of soft rubber, adapted to close the opening in the jewel, while a sleeve *h''* closely engages the rim *d''* of the intermediate section and thereby prevents any leakage into the cap, through capillary action.

In order to provide a smooth non-wearing point, I have equipped my pen with a centrally bored jewel *f*, which admits of high polish, and which is mounted in the tip section by means of a gold sleeve *f'*. This jewel

is preferable to any writing tip previously used in the art, and by reason of its non-wearing qualities and high polish, the said jewel is as satisfactory after years of use, 5 as when the pen was first constructed. As the feed wire is liable to slight wear, the block mounting the same is adapted to be screw-adjusted farther into the tip section, to compensate for such wear. The sides of 10 the threaded block g' are slightly cut away to permit of such adjustment, and facilitate the flow of ink, while the stem of said wire g , which passes readily through the block, is rearwardly upset or terminally enlarged 15 to form an abutment for maintaining the spring under tension. With the construction shown, the pen may be opened for filling with an ink dropper, if desired, merely by unscrewing the self-contained point and 20 tip section, which is threaded into the intermediate section to form a valve seat rearwardly therewith.

Ordinarily, the self filling feature will be relied upon by practically all users of the pen, 25 and I have employed the simplest and most advantageous form known to me for this construction, in explaining my invention, although not claimed herein. The barrel a is provided with no protruding part, and in consequence 30 an accidental discharge of the ink is practically impossible. In order to afford as great a capacity as possible, which is essential in the smaller sizes of fountain pens, I have provided merely the metal depressing strip b which is adapted to lie directly 35 against the bore of the barrel adjacent to the slot, and which is held in position by the pivoting hanger b' , removably secured at the end of the barrel by a threaded plug b'' . It is practicable to use a longer and 40 wider ink bag than is shown in the drawing, but ordinarily the proportions set forth are observed, for the reason that the extended end of the ink bag is more likely to be 45 cramped without being fully depressed by the hanger b' . Moreover, the motion of the bar when depressing the ink bag, is toward the nipple of the intermediate section, from 50 which it is spaced some distance, hence there is no tendency to displace or tear the rubber and thereby impair the efficiency of the pen. In Fig. 1, the bar is shown slightly depressed by an inserted coin indicated by dotted lines, while in Fig. 4, the fully depressed 55 position of the parts is also illustrated.

It will be found in use that the indirect system of vents afforded by the channel e^6 , and connected passages e^4 , e'' and e^3 , very largely avoid any accidental discharge of 60 the ink. Moreover, the inner vent e^3 is carried so closely to the tip as to insure a very short column of ink therein when the ink supply is nearly exhausted.

For the jeweled point, I preferably employ a polished agate or ruby jewel, cen-

trally tapered and bored to afford a slight terminal clearance for the wire g , and since this jewel is indestructible, a pen once selected to suit the writing of the user may be continued in use indefinitely and without 70 impairment.

Having now described the preferred embodiment of my invention, I claim as new, and desire to secure by Letters Patent, the 75 following:

1. In a fountain pen, the combination with an ink-container, of a tip-section having an inner vent extended closely adjacent to the writing point of the pen, an outer vent and an indirect connection between said vents positioned at a distance above the inner vent, substantially as set forth. 80

2. In a fountain pen, the combination with an ink-container, of a tip-section therefor, the same having a diagonal inner vent 85 interiorly extending closely adjacent to the outer extremity of said section, an external vent and a connecting transverse channel positioned at a distance above the inner vent uniting said inner and outer vents, substantially as set forth.

3. In a fountain pen, the combination with an ink-container, of a tip-section having an external vent formed therein, a channel into which said vent opens and a second 95 channel separated from the first by a slightly depressed wall, and a screw cap formed to engage the outer wall of said channel, substantially as set forth.

4. In a fountain pen, the combination with 100 an ink containing barrel, of a tip-section secured by screw-threads to said barrel, a valve seat provided interiorly of said pen against which the rear of the tip-section abuts, said tip-section having an ink passage 105 opening adjacent to the valve seat and an external vent provided in said tip-section below the valve seat, substantially as set forth.

5. In a fountain pen, the combination with a barrel, of an intermediate section screwing therein, an ink container within the barrel and connected with said intermediate section, a tip-section screwing into said intermediate section, a writing point thereon; said intermediate and tip-sections being separated by an exterior annular channel, the inner wall of which is slightly lower than the outer wall and said tip-section having an exterior annular channel formed therein adjacent to said depressed wall, and a cap 115 adapted to fit over the tip-section and barrel, substantially as set forth.

6. In a fountain pen, the combination with an ink-container, of an associated tip-section removably secured thereto, a writing point provided upon said tip-section; said section having two annular grooves of different depth positioned adjacent to the writing point and a vent extending from the inner and deeper groove to the interior of the 125 130

pen, and a screw cap engaging the walls of the outer and shallower groove, substantially as set forth.

7. In a fountain pen, the combination with 5 an ink-container, of a tip-section and its writing point secured to said ink-container by a screw threaded connection; said tip-section having an inner vent extending downwardly adjacent to the writing point, 10 an outer vent and a connecting interior annular groove uniting said vents, whereby the ink and air are caused to travel in opposite directions through the connecting passages afforded by said tip-section, substantially as 15 set forth.

8. In a fountain pen, the combination with an ink-containing barrel of a tip-section therefor; the same having an external vent leading toward the upper portion of the tip 20 section, and an internal vent leading toward the lower portion and opening closely adjacent to the extremity of the tip-section and a connection between said vents positioned at some distance from the outlet of the inner 25 vent whereby the air is caused to travel in opposite directions within the tip-section, substantially as set forth.

9. In a fountain pen, the combination with 25 an ink-containing barrel and its shouldered tip-section, of a screw cap fitting over and 30 interiorly abutting the shouldered portion of the tip-section; said shouldered portion

having two annular grooves and an annular wall intermediate thereof sufficiently depressed to remain out of engagement with 35 the screw cap, substantially as set forth.

10. In a stylographic pen, the combination with an ink-containing reservoir and its connected tip-section, of a centrally bored tapered jewel forming the writing point thereof, 40 a non-corrosive mounting sleeve therefor and a feed wire extending within the bore of said jewel, substantially as set forth.

11. In a stylographic pen, the combination with an ink-container and its connected 45 tip-section, of a stylographic point for said tip-section comprising a centrally bored and polished jewel tapering interiorly and mounted within the tip-section, and a feed wire extending through the bore of said 50 jewel, substantially as set forth.

12. In a stylographic pen, the combination with an ink reservoir and its connected tip-section, of a non-wearing centrally bored writing point terminating said tip-section, 55 a feed wire extending through said point, and a screw-adjustment for said feed wire, substantially as set forth.

In testimony whereof I do now affix my 60 signature in the presence of two witnesses.
